UNITED STATES PATENT OFFICE.

THOMAS H. SEELY, OF MALDEN, MASSACHUSETTS, ASSIGNOR TO UNITED SHOE MACHINE CORPORATION, OF PATERSON, NEW JERSEY, A CORPORATION OF NEW JERSEY.

FASTENING-INSERTING MECHANISM FOR LASTING MACHINES.

Application filed July 26, 1918, Serial No. 246,835. Renewed June 9, 1921. Serial No. 476,362.

To all whom it may concern:

Be it known that I, THOMAS H. SEELY, a citizen of the United States, residing at Malden, in the county of Middlesex and 5 State of Massachusetts, have invented certain Improvements in Fastening-Inserting Mechanism for Lasting Machines, of which the following description, in connection with the accompanying drawings, is a specification, like reference characters on the drawings indicating like parts in the several figures.

The invention to be hereinafter described relates to machines for manufacturing boots 15 and shoes, and more particularly, though not exclusively, to lasting machines whereby the upper materials are worked over a last and innersole and secured either permanently or temporarily in lasted position. 20 Broadly considered, the invention is not confined for use in connection with any particular type of lasting machine, but for the purpose of making clear its construction and mode of operation, it will herein be described as associated with that class of machines in which the upper materials are worked into lasted position by repeated operations on different portions and secured by fastenings driven through the overworked 25 portions as the work progresses. A machine of this general character is shown and described in United States Letters Patent No. 584,744, dated June 15, 1897.

In lasting welt shoes, it is the custom to 30 fully drive small fastenings or tacks through the marginal portions of the overworked upper and ears of the counter, or it may be about the entire heel seat to permanently secure the upper in lasted position, but at 35 other portions of the shoe, longer fastenings are partially driven to temporarily hold the upper in overworked or lasted position until after or during the welt-attaching operation, when they are withdrawn. In lasting 40 "McKay" shoes, the fastenings are or may be fully driven around the entire shoe to permanently secure the upper in overworked or lasted position, but in such case at the toe and heel seat portions of the shoe, longer 45 tacks are required than at other portions of the shoe, owing to the increased thickness of the upper materials through which the fastenings are driven. Thus, in the lasting 50 operation, whether upon a welt or McKay

shoe, a change in the character, kind, or size 55 of the fastenings furnished must be made from time to time.

Heretofore, it has been the custom to provide a fastening-supplying means usually in the form of a raceway having two or more 60 channels or guides each supplying a different character, kind, or size of fastening and to place one or the other of such channels or guides in operative relation with a separating mechanism for supplying the desired 65 fastening to a nail block by which the fastening was placed in inserting position. In this prior construction, however, the first fastening presented to the inserting mechanism or driver after a change of the raceway to place the desired channel or guide in 70 supplying position, was of the character, kind, or size previously in use, and consequently not suited to the new portion of the shoe presented for treatment. It has therefore been necessary for the attendant or operative to run the machine "idle" or without a shoe for at least one cycle of operation after a change has been made in the 75 character, kind, or size of the fastenings to 80 be used, thus causing loss of one or more fastenings after each change, lack of economy in the machine operation, and an accumulation of loose fastenings on the floor.

An important feature of the present invention, therefore, consists in means for selectively presenting the desired character, kind, or size of fastenings to the inserting mechanism including the first fastening presented after a change has been made by 85 the supplying means in the character, kind, or size of the fastenings to be supplied by it.

In accordance with this feature of the invention a receiving means or member is provided between a plurality of sources of tack 90 supply for tacks of different kinds and the inserting mechanism which means is arranged to receive and hold a separated tack of each of the different kinds and means under control of the operator is provided 95 to determine which of the separated tacks will be delivered to the inserting mechanism.

As herein shown the receiving means comprises a presenter located between the separating mechanism and tack block and having a plurality of pockets, the presenter being movable in different paths in accord-

ance with the character, kind, or size of fastening supplied by the supplying means, to position one or another pocket in line with the inserting mechanism or driver.

5 A further feature of the invention consists in a plurality of sources of tack supply, for example raceways, for different kinds of tacks, a separator for separating tacks from the source of supply, and means, for example the presenter referred to, for receiving a tack of each kind from the separator.

In some kinds of shoes, the fastenings inserted in the heel seat or through the ears of the counter are located further from the 15 edge of the shoe than are the fastenings at other parts of the shoe in order that the heel seat fastening may not be in the way of the nails which secure the heel to the shoe. When a change in the character, 20 kind, or size of the fastenings to be inserted is made, therefore, it is desirable that the position of the shoe relative to the path of the inserting means or driver be changed correspondingly that the particular fastenings to be inserted be located the desired 25 distance from the edge of the shoe. Another important feature of the invention, therefore, consists of movable work rests or gages which are moved relatively to present 30 the proper rest or gage to the shoe simultaneously with the change in the character, kind, or size of the fastenings to be furnished by the supplying means so that the first, as well as the succeeding operations of 35 the inserting mechanism may insert proper fastenings at the desired distance from the edge of the shoe.

Upon the completion of one shoe, the attendant or operative usually maintains his 40 foot upon the starting treadle while he reaches for another shoe, and the machine consequently continues in operation. During this interval a loss of fastenings occurs because there is no shoe positioned in the 45 machine to receive them. It has therefore been proposed to suspend the operation of the fastening-separating mechanism when a shoe is not presented to the machine for treatment, but the fastening carrier or tack block, as it is usually termed, was moved to driving position and if the driver remained in operation, it would expel any fastening contained in the pocket of the carrier or tack block, with the result that no fastening 50 would be presented to the driver on its first action after another shoe was presented for treatment. Another important feature of the present invention, therefore, 55 consists of means for causing the fastening-presenting mechanism to retain the fastener-carrying pocket away from the action of the inserting mechanism when a shoe fails to be in position for treatment during the operation of the machine. This feature of the 60 invention is carried into effect by a pre-

senter which, during the operation of the machine when a shoe is positioned for treatment, carries a fastening from the separating mechanism to driving position, but which, during the operation of the machine 70 without a shoe to receive the fastenings, does not move the fastening to driving position. This is advantageous because, among other things, it obviates the necessity of some means for suspending the operation of the driver when a shoe is not in position for treatment and yet insures the presentation of a fastening to the first action of the driver when a shoe is placed in the machine. 80

It is usual in machines of this type to shift the raceway in order to bring one or another guide or channel in line with the opening in the block of the separating mechanism. Much care and attention have 85 therefore been required in constructing these parts in order that they might be properly co-related and relatively moved. A further important feature of the present invention consists in adjustable connections 90 between the raceway and its moving means for changing the path of raceway movement and the amplitude or extent of such movement. As a result, the raceway parts may be made with less accuracy and precision as to details, and then co-related with the block of the separating mechanism to bring the guides or channels in proper position when the raceway is shifted. 95

The above and other features of the invention will be hereinafter described in connection with the accompanying drawings showing one good, practical form thereof, and the novel features will then be definitely defined by the claims. 100

In the drawings:

Figure 1 shows in side elevation, the head portion of a lasting machine containing the present invention;

Fig. 2 is a horizontal section substantially 110 on the line 2-2, Fig. 1, on an enlarged scale and with some of the parts omitted;

Fig. 3 is a front view, partly in section, of mechanism shown in Fig. 1, some of the parts being omitted for clearness of illustration; 115

Fig. 4 is an enlarged detail partly in section, showing part of the tack carrier and block, and the presenter associated therewith; 120

Fig. 5 is a section on the line 5-5, Fig. 4;

Fig. 6 is a perspective view showing the fastener presenter detached;

Fig. 7 is a plan view partly in section, showing the work gages and associated parts detached; 125

Fig. 8 is a plan view in detail showing more particularly the hand lever and lock for the controlling means;

Fig. 9 is an enlarged sectional plan view 130

showing more particularly the association and relation of the tack-separating mechanism, the presenter, and tack block when a shoe is not presented to the machine for treatment; and

Fig. 10 is a view similar to that of Fig. 9, showing the same parts in another position and the presenter delivering a tack to driving position.

10 The machine frame comprises a column or standard 1 on which rests the head 2 for supporting the operating parts, and as usual in such machines, a treadle rod 3 extends downward from the head for starting 15 and stopping the machine operation. The head 2 supports a cam shaft 4 which may be driven from a pulley 5 operated by belt connection with a suitable source of power, as usual. The shaft 4 has connected there- 20 with a cam 6 for operating the grippers, a cam 7, Fig. 3, for lifting the driver-bar 8, and a cam 9 for operating the tack carrier slide 10. A spring impelled arm 11, Fig. 1, acts to impel the driver bar 8 and driver 12 25 downwardly for inserting or driving the fastenings into the work. The parts so far described may be of the usual construction and operation.

The machine illustrated is more particularly designed to treat "welt" shoes, wherein it is customary to partly drive long fastenings or tacks along the sides and fully drive shorter fastenings or tacks through the ears of the counter or about the heel seat. The 30 driver-bar 8, therefore, has a collar 13 adapted to stop the downward movement of the driver by engagement with stops 14 when long tacks are to be partly driven, but permit full downward movement of the 35 driver when the stops 14 are withdrawn that the shorter tacks may be fully driven. The stops 14 are operatively connected to the shaft 15, which, as will more fully appear, is turned by means under control of 40 the attendant to place the stops 14 in or out of operative position in conformity with the character of tacks to be driven. Herein, the terms "fastenings" and "tacks" are used in the broad sense, to designate devices 45 which are separately or independently inserted or driven into the work.

The slide 10 has a front portion 16 from which extends the tack-block 17, Fig. 4, the lower surface 18 of which constitutes a 50 wiper to wipe or lay the marginal portions of the upper materials over the innersole of a shoe presented for treatment. The front portion of the tack-block has a driver passage 19 through which the driver 12 passes and forces a tack into the work during the tack-driving operation. Between the upper and lower surfaces of the tack block at each side thereof, a recess is formed for the accommodation of the tack-guiding 55 springs 20, which may be of usual construc-

tion. The tack-block preferably has its lower or wiping surface formed of hardened steel secured thereto by means such as the pin 21 and bolt 22, Fig. 4.

The fastening or tack-supplying means 70 consists of a raceway 23, Figs. 2 and 3, having in the present instance two guides or channels 24 and 25 for supplying different kinds or sizes of tacks, and the raceway is adapted to be shifted to place either guide 75 or channel in operative relation with the receiving opening of a tack-guide or separator block 26, as is customary. Cooperating with the tack-guide 26 is the separator 27 provided with a tack-separating slot, as usual, and reciprocated in front of the raceway by the toothed segment 28 pivotally mounted at 29 and yieldingly connected to an arm 30 carrying a roll 31 adapted to be engaged and moved at times by a cam arm 32 to be more fully described.

The slide 10 has a projecting portion 33 to which is pivoted at 34 a swing plate 35 extending over and some distance above the tack-block 17 and carrying the cam arm 32. 90 Pivotally mounted on the swing plate 35 at 36 is an arm 37 by which tacks separated from the supplying means are individually transported or presented to tack-driving position above the driver passage 19 in the tack-block. For the purpose of identification, this arm 37 may be designated a presenter, because it takes the desired fastenings from the separating mechanism and delivers or presents them to driving position. 100

In the present instance, the presenter is located between the swing plate 35 and the tack-block and is provided with two tack-holding pockets corresponding to the number of guides or channels in the raceway or the number of different kinds or sizes of tacks to be supplied. The tack-holding pockets may be variously contrived, but as more clearly shown in Fig. 6, they are preferably formed by three blocks 38, 39 and 40 105 each having complementary portions of a tack-holding pocket and detachably held in the end portion of the presenter 37. The presenter 37 in the present instance is split longitudinally for a part of its length, as at 41, to form two spring arms 42 and 43, and the blocks 38, 39 and 40 have interlocked shank portions 44, 45 and 46, which are irregularly-formed as shown, and correlated with each other and the spring side arms of the presenter, the construction being such that while the blocks or tack-pockets may be appropriately secured to the presenter, they may yield or separate slightly to permit the tacks to be driven and may also be readily removed when desired. 115

The presenter 37 has a rearward extension 47 to which is connected at 48 a link 49 which, under the means to be hereinafter described, serves to control the path of 120 125 130

movement of the presenter and determine thereby which of the two tack-pockets 50, 51, shall be moved into position above the driver passage 19 in the tack-block when the parts are in position to deliver a tack to the inserting mechanism. The rear extension of the presenter is in the present instance formed to embrace the portion 16 of the tack carrier slide and the embracing portion 10 thereof is sufficiently large to permit swinging movement of the presenter by the link 49, as will more fully appear.

The swing plate 35 is under the influence of a spring which normally holds the swing plate and perforce the presenter 37, pivoted thereto in rearward position relative to the tack-block, as indicated in Fig. 2. In the present instance of the invention, the swing plate has projecting therefrom an arm 52 carrying a roll 53 against which the spring 54 secured to the slide 10 bears, the construction being such that the pressure of the spring 54 against the roll 53 normally holds the swing plate 35 and presenter 37 in rearward position, as described.

Secured to the shaft 15 by suitable means such as the clamps 55 and bolts 56, Fig. 2, is a casting 57. The casting 57 has connected thereto a handle 58 by which the casting 30 57 and shaft 15 connected thereto may be rocked from time to time, as desired. In the present instance of the invention the handle 58 has a portion 59 carried by lugs 60 projecting from the casting, and extending 35 upwardly from the portion 59 are the wings 61 which, as more clearly indicated in Fig. 8, may be constituted as locking lugs, the end portions 62 of which are adapted to ride along surfaces 63 and engage the locking 40 recesses 64 at either end of the handle movement. Pivotaly mounted at 65 in a suitable bracket 68 are the arms 66 connected by a spring 67 as indicated in Fig. 8, to insure locking engagement of the locking 45 lugs or wings 61 with either of the locking recesses 64. The above-described construction is a good, practical form of attendant-controlled means for swinging or rocking the casting 57 and shaft 15, but obviously 50 the details of this construction may be varied within wide limits without departing from the spirit of the invention. As hereinbefore described, the rear portion of the presenter 37 is connected to a link 49 for controlling the movements of the presenter. In the present instance of the invention, the link 49 is pivotally connected at 69 to the casting or part 57 which is rocked by the hand-piece 58, the construction being such 60 that by moving the hand-piece 58 into the one or the other of its positions, as indicated in Fig. 8, the rear end portion of the presenter 37 will be moved laterally so that as the nail-block and tack presenter move forwardly and the tack presenter is moved

relatively to the tack block, as will more fully appear, either one of the tack-pockets 50 or 51 may be caused to coincide with or carry a tack into position above the driver 70 passage 19 in the tack block.

The raceway 23 is also connected to the hand-piece 58 so that upon movement of the hand-piece, the raceway is moved to bring one or the other of its guides or channels into co-operative relation with the usual opening in the tack-separator block 26 and the tack presenter 37 is likewise shifted to change its path of movement and thereafter take from the tack-separating mechanism 75 the desired kind or size of fastening to be inserted into the new portion of the shoe presented for treatment. When moved to one position by the link 49, the tack presenter 37 is adapted to take tacks from the separating mechanism of one kind or size and when shifted to the other position by the link 49, is adapted to take tacks of the other kind or size from the tack separating mechanism, the construction being such that when the tack presenter 37 moves forwardly to 80 present a tack to driving position, each of the pockets 50 and 51 carries a tack or fastening, one tack or fastening being of one kind or size, and the other tack or fastening being of the other kind or size. When the tack pockets in the presenter are empty for any reason, as for instance when the machine is first started, it will, of course, be necessary to run the machine idly through a cycle or two first with the lever 58 in one 85 position and then with it in the other position, the rest 83 being held up in order to permit tacks to be separated and the tack pockets to be filled. Subsequently, whenever a shift is made in the raceway, and 90 perforce, in the tack presenter, by the attendant, the tack presenter 37 will present a tack of the desired kind or size to the first action of the driver after a change in the kind or size of tacks to be driven. The 95 path of movement of the tack presenter in delivering tacks to driving position by the tack-pocket 51, for instance, is indicated in Fig. 2, wherein the arrowed dotted line represents the path of movement of the pocket 100 51 from tack-receiving to tack-delivering 105 positions.

When no shoe is presented to the machine for treatment, as for instance, when the attendant finishes one shoe and reaches for another, without stopping the machine, it is desirable that the presentation of tacks to driving position be suspended. This is particularly true where the driver itself continues in operation, because in such event, should a fastening or tack be carried to driving position, even though the separating mechanism be rendered inoperative, the last tack delivered for driving would be expelled, and on the presentation of a shoe to 110 115 120 125 130

the machine, the first action of the driver would find no tack in position to be driven. The present invention provides means which, when a shoe is not in position for 5 treatment, will not move into tack-driving position the next tack to be driven.

The arm or bracket 70, Fig. 1, has adjustably secured thereto as by the slot connection 71, an arm 72 to which is connected by parallel link motion devices 73, the shoe rest carrier 74. One of the links 73 is extended upwardly as indicated in Fig. 1 to form a toe 75, Figs. 1 and 2, adapted to bear upon the arm 76 of a lever pivoted at 77 on the bracket 70 and normally under the influence of a spring 78 which, in the present instance of the invention, is shown (Fig. 2) as constituted by a spring plunger, the head of which is adapted to bear against the side 20 of the lever arm 79. The arm 79 carries an adjustable block 80. Rising from the swing arm 35 is a shouldered lug 81. This may be variously contrived, but in the present instance, comprises a piece formed separate from the arm 33 adjustably secured thereto by the bolt 82, the construction and relation of parts being such that if a shoe is not presented to the machine for treatment, the shoe rest 83 is not raised and the 25 arm 79, under the action of the spring 78, holds the block 80 out of the path of movement of the shouldered lug 81 as the latter moves forwardly with the tack-carrier slide 10, the effect being that the spring 54, acting thru the arm 52, maintains the swing plate 35 in its rearward position relative to the tack block 17, as indicated in Fig. 9, so that as the tack block and, perforce, the swing plate 37, move forwardly with 30 the tack carrier slide, the presenter 37 is not moved relatively to the tack block and so fails to present one of its tack-holding pockets in position above the driver passage in the nail block, so that the fastenings 35 or tacks in the pockets of the presenter remain therein. On its driving stroke, the 40 driver 12 will pass in front of the presenter 37 and through the driver passage 19 of the tack block. The position of parts when 45 no shoe is presented to the machine for treatment, is represented in Fig. 9, wherein it will be noted that the tack carrier slide has moved forwardly to place the driver 50 passage 19 of the tack block in driving position, but the presenter 37 carrying tacks in each of its tack-holding pockets, has not been moved relatively to the tack block to 55 present either pocket in driving relation with the driver passage 19.

60 When no shoe is presented for treatment during the operation of the machine, it is likewise desirable that the tack-separating mechanism be rendered inoperative, and this is effected in the present instance of the invention by the cam-carrying arm 32 which,

since the swing plate 35 remains in the position indicated in Fig. 9, is not swung outwardly sufficiently far to cause actuation of the tack-separating mechanism during the forward movement of the tack-carrier slide. 70

When, however, a shoe is presented to the machine for treatment, the shoe rest 83 is raised and the arm 79 of the pivoted lever is moved to carry the block 80 into the path of movement of the shouldered lug 81 as the latter advances with the tack-carrier slide 10. On contact of the parts 80 and 81, the swing plate 35 is moved about its pivotal mounting 34 as indicated in Fig. 10, with the result that the presenter 37 pivoted to 80 the plate 35 is caused to carry a tack to tack-driving position above the driver passage 19 of the tack block.

It is desirable that movement of the presenter 37 and tack block as the parts advance to driving position, shall be so correlated that one of the pockets 50 or 51 of the presenter may be accurately positioned above the driver passage 19 of the tack block; and to this end, the present invention provides in addition to the locking means for the hand-piece 58, a safety device which will prevent movement of the hand-piece during the time the machine is operating upon a shoe. To this end, the arm 79, Fig. 2, is 95 provided with an inturned portion 84 adapted to engage the end portions of a lug 85, Figs. 2 and 3, extending from the casting 57 when the arm 59 has been moved, as hereinbefore described, by a shoe presented to the machine for treatment. So long as the shoe is held in the machine, the inturned end 84 of the arm 79 will remain in the path of movement of the lug 85 and therefore act as a safety device to prevent manipulation 100 of the hand-piece 58 while the machine is operating upon a shoe. In the present instance of the invention, the end portion of the lug 85 is preferably formed by a separate piece of hardened metal 86 secured to the lug 85 by appropriate means such as the bolt 87. Hereinbefore it was stated that the raceway 23 was moved to bring either of its guides or channels 24 or 25 into co-operative relation with the usual opening in the tack-separator block by the hand-piece 58, and to this end the raceway 23 is connected 110 to the casting 57. The connections in the present instance of the invention are of 115 novel character and construction, and effect for the first time in the art a ready means of adjusting both the position of the path of movement of the raceway and also its amplitude of movement, so that in the manufacturing of the parts, the great accuracy 120 and care heretofore required becomes unnecessary. In the present instance of the invention in this respect, the casting 57 has adjustably secured thereto a block 88, Fig. 125 3, which, by means of a bolt 89 and slot 90,

may be adjusted to different positions relative to the casting and then secured in such adjusted position. Extending from the block 88 is a lug 91 to which is pivotally connected at 92, one end of an arm 93, the other end of which carries a sleeve 94 thru which the rod 95 extending from the raceway 23, passes. The rod 95 is preferably screw-threaded into the sleeve 94, as at 96, 10 Fig. 3, and a lock nut 97, Fig. 2, serves to hold the parts in adjusted position. The connection between the rod 95 and the arm 93 may, of course, be variously contrived to afford adjustment in the length of the rod 15 95 between the arm 93 and the raceway, but that described has been found to be a good, convenient form of this feature of the invention. By the character of adjustment last described, one of the guides or channels 24 or 25 of the raceway 23 may be accurately 20 registered with the opening in the tack-separator block, and by means of the hand-piece 58, the raceway 23 may then be shifted to bring the other guide or channel into approximate registration with the opening in 25 the tack-separator block. By adjustment of the block 88 as hereinbefore described, the raceway channel may then be accurately brought into registration with the opening 30 in the tack-separator block, such adjustment being made without disturbing the previous adjustment and the two adjustments serving to adjust the position of the raceway in its 35 path of movement, and the amplitude of such movement.

As hereinbefore indicated, it is desirable to drive the fastenings or tacks about one portion of the shoe at a different distance from the edge of the shoe than fastenings 40 are driven at another point of the shoe; and to this end two gages are employed which are technically designated the "thin" and the "thick" gages. The thin gage is usually employed along the shank and forepart of the 45 shoe, while the thick gage is employed about the ends of the shoe as, for instance, at the toe portion and about the heel seat. It therefore becomes necessary to shift the 50 gages simultaneously with a shift in the kind or size of fastening or tack to be supplied.

In the present instance of the invention this feature is carried into effect by the construction more clearly shown in Figs. 2, 3 55 and 7.

Fixed to but adjustably mounted upon the head frame is the plate 98 having a slot 99 thru which passes the securing bolt 100, the construction being such that the plate 98 60 may, by loosening the bolt 100, be adjusted bodily toward and from tack driving position. Supported for movement toward and from tack-driving position on the plate 98, is the gage carrier 101. This sliding 65 connection between the fixed and movable

plate may be variously contrived, and as indicated in Fig. 3 is secured by appropriate undercut and interengaging guiding portions between the two. Rotatably mounted in the gage carrier 101 is a shaft 102 on 70 which is loosely mounted the thin gage 103, and to which is fixedly secured the thick gage arm 104, having the thick gage 105. Secured to the shaft 102 is a segment gear 106 which engages the teeth 107 of a rack-bar 108 mounted to slide longitudinally. The rack-bar 108 has a series of teeth 109 which engage the teeth 110 on a toothed segment 111 which is fixed to the rotatable pin 112. Also fixed to the pin 112 is the arm 113 pivotally connected by the link 114 to the casting 57 as indicated in Figs. 2 and 3. In the present instance of the invention, the casting 57 has a downwardly-extending portion 115 to which is pivotally connected at 85 116 the link 114.

The pin 112 is mounted in the gage carrier slide 101 and has adjustably secured thereto the block or projection 117, Fig. 7, the end portion 118 of which is adapted to engage an 90 inclined slot or opening 119 formed in the fixed plate 98, the construction being such that upon manipulation of the hand-piece 58, movement will be imparted to the gage carrier slide 101 thru the link 114 and adjustable connection with the slot 119 of the fixed plate 98, and simultaneously with such movement, the segment arm 111 will actuate the rack 108 to cause movement of the thick 95 gage to or from work-engaging position. 100

When driving tacks or fastenings with the thin gage 103 in use, the tacks are driven at a distance from the edge of the shoe determined by adjustment bodily of the plate 98 and gage carrier slide 101, the thick edge 105 gage being then in inoperative or lowered position. When the thick edge gage is moved to operative position, the slide 101 should be moved rearwardly a distance equal to the difference between the distance from the shoe edge at which tacks are driven when the thin gage is in position and the distance from the shoe edge at which tacks are driven when the thick gage is in position, plus the amount that the thick gage projects 110 forwardly of the thin gage. In the construction shown herein these adjustments are effected, as follows: To adjust the thin edge gage to the desired position relative to the driver path, the hand-piece 58 is manipulated to move the thick gage out of operative 115 position and swing the block 117 into alignment with the inclined slot 119. If the thin edge gage is not at this time in position to locate fastenings at the desired distance 120 from the edge of the shoe, the bolt 100 is loosened and the fixed plate 98 together with the gage carrier 101 and its connected parts, are moved to place the thin edge gage 103 in 125 proper position. The thick edge gage is 130

then adjusted by swinging the hand-piece 58 to place the parts in the position indicated in Fig. 7. The block 117 is then loosened from its connection with the bolt 112 as by manipulation of the nut 120 and is moved lengthwise to place the thick edge gage in the desired position, it being understood that owing to the inclination of the slot 119, such endwise movement of the block 117 will cause movement of the gage carrier slide 101. The parts being adjusted in the desired position, the block 117 is clamped in place. Thereafter, by manipulation of the hand-piece 58 as hereinbefore described, to change the kind or size of tacks or fastenings to be supplied, the appropriate edge gage is presented to the work, and located to cause the fastenings to be driven at the proper distance from the edge of the last.

20 What is claimed is:

1. In a machine of the class described, the combination of continuously-operating inserting mechanism, means for supplying selectively fastenings of different characters, 25 means for maintaining a supply of separated fastenings of each character, and means for presenting either character of separated fastenings to the inserting mechanism including the fastening first presented after a 30 change in the character of fastening to be supplied by the supplying means has been made.

2. In a machine of the class described, the combination of continuously-operating fastening inserting mechanism, means for supplying fastenings of one character for insertion in one portion of a shoe and fastenings of a different character for insertion in another portion of the shoe, means for controlling the supplying means which is movable to change the character of fastening supplied by it, a separator for separating fastenings from said supplying means, and means receiving tacks from the separator and acting 45 to present the desired character of fastenings to the inserting mechanism including the fastening first presented after a movement of the controlling means.

3. In a machine of the character described, 50 the combination of fastening-inserting mechanism, mechanism for supplying fastenings of different kinds, means for maintaining a supply of fastenings in separated condition, and means for insuring the presentation of a 55 separated fastening of the desired kind to the first action of the inserting mechanism after a change in the kind of fastening to be supplied.

4. In a machine of the character described, 60 the combination of a continuously-operated driver, mechanism operated in a previous cycle to supply fastenings of different kinds or sizes, a separator for separating fastenings from said supplying means, and means 65 for presenting a separated fastening of the

desired kind or size to the first stroke of the driver in the cycle following a change in the kind or size of fastening to be supplied.

5. In a machine of the class described, the combination of a driver, means for supplying fastenings of different kinds or sizes, means for separating for subsequent use fastenings of each kind or size, and means for presenting the desired kind or size of separated fastenings to the driver including the first fastening to be driven after a change in the kind or size of fastening to be supplied by the supplying means.

6. In a machine for driving fastenings of one character in one part of a shoe and fastenings of a different character in another part of a shoe, the combination of a driver, means under manual control for selectively supplying either of the two characters of fastenings, a separator for separating fastenings of either character, and means for presenting a separated fastening of the selected character to the first stroke of the driver when a change is made in the character of fastenings to be furnished by the supplying means.

7. A machine for driving fastenings of one character in one part of a shoe and fastenings of a different character in another part of the shoe, comprising, in combination, a driver, fastening-supplying means for supplying fastenings of different characters appropriate to the part of the shoe being treated, a separator, and means co-operating with the separator to maintain a supply of separated fastenings of the different kinds and acting to present to the first stroke of the driver when a change is made from one part of the shoe to another a separated fastening of the appropriate character to be driven in that part of the shoe.

8. A machine for driving fastenings of one character in one part of a shoe and fastenings of a different character in another part of the shoe, comprising, in combination, a driver, fastening-supplying means for supplying fastenings of different characters appropriate to the part of the shoe being treated, a separator for separating fastenings of either character, and means for presenting to the first stroke of the driver when a change is made from one part of the shoe to another, a separated fastening of the appropriate character to be driven in that part of the shoe, and means for simultaneously varying the distance from the edge of the shoe at which the fastenings are to be driven.

9. In a machine of the character described, the combination of a movable raceway provided with a plurality of channels for supplying fastenings of different kinds or sizes, fastening-inserting mechanism, a separator, a fastening presenter for presenting the different kind or sizes of separated fastenings

to the inserting mechanism, and means rendered effective as the raceway is moved to cause the presenter to present to the first operation of the inserting mechanism a fastening of the kind or size to be furnished by the raceway.

10. In a machine of the class described, the combination of a movable raceway for supplying different kinds or sizes of tacks, a driver, a presenter for presenting tacks to the driver, and means under control of the attendant for moving the raceway and shifting the presenter that the first tack presented to the driver after movement of the raceway shall be of the kind or size to be thereafter furnished by the raceway.

11. In a machine of the class described, the combination of a raceway movable to different positions for supplying different kinds or sizes of tacks, a tack driver, a presenter having a plurality of tack-carrying pockets to present tacks singly to the driver, and means operable at will to change the kind or size of tacks supplied by the raceway and cause the presenter to present to the first stroke of the driver a tack of the kind or size furnished by the raceway.

12. In a machine of the character described, the combination of a driver, a tack-block having a driver passage, means including a tack separator for selectively supplying tacks of different kinds or sizes, a tack presenter between the tack block and supplying means for presenting tacks for the action of the driver, and means for shifting at will the tack-supplying means to change the kind or size of tacks to be supplied by it and to cause the presenter to present to the driver on its first stroke after a shift of the supplying means a tack of the kind or size to be furnished by the supplying means.

13. In a machine of the class described, the combination of a driver, means for supplying different kinds or sizes of fastenings, a tack presenter having a plurality of pockets each to carry respectively its kind or size of fastening as furnished by the supplying means, means for causing the supplying means to furnish fastenings of one or another kind or size as desired, and means for effecting movement of the presenter to present fastenings of the desired kind or size to the driver including the first fastening to be driven after a change in the kind or size.

14. In a machine of the class described, the combination of a driver, means for supplying different kinds or sizes of fastenings, a tack presenter having a plurality of pockets to carry respectively fastenings of the different kinds or sizes furnished by the supplying means, means operable at the will of the attendant for causing the supplying means to furnish fastenings of one

or another kind or size as desired and for effecting movement of the presenter to present fastenings of the desired kind or size to the driver including the first fastening presented to the driver after a change in the kind or size has been made.

15. In a lasting machine, the combination of a movable raceway for supplying different kinds or sizes of fastenings, a driver, a presenter having pockets for holding different kinds or sizes of fastenings, a hand lever, and connections between the hand lever, the raceway, and presenter for changing the kind or size of fastening to be supplied by the raceway and causing the presenter to present to the driver on its first operation after such change a fastening of the kind or size to be supplied by the raceway.

16. In a lasting machine, the combination of a movable raceway for supplying different kinds or sizes of fastenings, a driver, a presenter having pockets for holding different kinds or sizes of fastenings, a hand lever, connections between the hand lever, the raceway, and presenter for changing the kind or size of fastening to be supplied by the raceway and causing the presenter to present to the driver on its first operation after such change a fastening of the kind or size to be supplied by the raceway, and means for simultaneously changing the distance from the edge of the shoe at which the new fastenings are to be driven.

17. In a machine of the class described, mechanism for supplying fastenings of different kinds or sizes, a plurality of relatively movable shoe rests, a driver, a presenter for taking fastenings from the supplying mechanism and presenting them to the driver, and means for causing the supplying mechanism to change the kind or size of fastening supplied by it, and simultaneously to relatively move the shoe rests and cause the presenter to present to the driver on its first operation following such change a fastening of the kind or size being furnished by the supplying mechanism.

18. In a machine of the class described, the combination of tack-supplying means to supply tacks of different kinds or sizes, a single separator for separating either kind of tacks, a thin edge gage, a thick edge gage, means for moving the thick edge gage toward and from operative position and simultaneously changing the kind or size of tacks furnished by the supplying means, and means effective on the first cycle of the machine operation following such change to present a separated tack of the new kind or size for insertion in the shoe.

19. In a machine of the character described, the combination of means for supplying different kinds or sizes of fastenings,

separating mechanism for separating fastenings from the supplying means, a driver, a block having a driver passage and movable toward and from the work, a presenter having two pockets to receive fastenings from the separating mechanism and means for effecting movement of the presenter to locate one of the pockets in alignment with the driver passage in the block to furnish 10 the kind or size of fastenings supplied by the supplying means.

20. In a machine of the class described, the combination of a raceway having two channels for supplying tacks, a driver, a 15 tack block having a driver passage, a presenter having two tack pockets for holding tacks furnished from the channels of the raceway, and hand-controlled means for adjusting the raceway and simultaneously adjusting the presenter to cause one or the other pocket to be aligned with the driver passage during the operation of the machine.

21. In a machine of the character described, a raceway for supplying tacks of different kinds or sizes, a thin work rest and a thick work rest, a tack presenter having a plurality of tack pockets for receiving tacks of different kinds or sizes from 30 the raceways, and hand-controlled means for simultaneously shifting the raceway, moving the work rests relatively, and adjusting the presenter.

22. In a machine of the character described, a raceway for supplying tacks, tack-separating mechanism, a tack block, a driver, a tack presenter for taking tacks from the separating mechanism and delivering them singly to the tack block and driver, and means for suspending the effective operation of the tack-separating mechanism and tack presenter when a shoe fails to be presented to the operation of the machine.

23. In a machine of the class described, a raceway for supplying tacks of different kinds or sizes, tack-separating mechanism, a tack block having a driver passage, a tack presenter having a plurality of tack pockets each to carry a tack of a different kind or size delivered by the tack-separating mechanism, means for moving the tack presenter to align one of its pockets with the driver passage, and means acting to suspend the effective operation of the tack-separating mechanism and tack presenter when a shoe is not presented to the machine.

24. In a lasting machine, the combination of means for supplying fastenings, a separator for separating fastenings from the 60 supplying means, a presenter, means for giving the presenter full movement to carry a fastening from the supplying means to driving position when a shoe is presented for treatment and for giving the presenter a less movement when a shoe is not presented

for treatment that the fastening carried by the presenter may not be placed in driving position.

25. In a lasting machine, the combination of means for supplying fastenings, a separator for separating fastenings from the supplying means, a reciprocating tack block, a presenter for taking fastenings from the separator and presenting them over the tack block in position to be driven, and means for suspending the effective operation of the separator and the presenter when a shoe is not position to be treated by the machine. 70 75

26. In a lasting machine, the combination of tack-supplying means, a tack block having a driver passage, tack-separating mechanism, a tack presenter, means for moving the tack block and tack presenter for placing the driver passage in driving position 80 85 and a tack carried by the presenter in line with the driver passage when a shoe is in position to receive the tack and for modifying the movement of the tack presenter so that it will not present a tack in line with the driver passage when a shoe is not in position to be treated. 90

27. In a lasting machine, a tack block slide carrying a tack block having a driver passage, an arm mounted for movement with and relative to the slide, a tack presenter having pockets for holding different kinds or sizes of tacks and mounted for movement with and relative to said arm selectively to present one of the tack pockets 100 in line with the driver passage. 95

28. In a lasting machine, a slide carrying a tack block having a driver passage, a tack presenter having a plurality of tack pockets for holding different kinds or sizes 105 of tacks, means for causing the presenter to move with and relative to the slide to present one of the tack pockets in line with the driver passage when a shoe is positioned in the machine for treatment and suspending the relative movement of the presenter and slide when a shoe is not positioned for treatment. 110

29. In a lasting machine, means for supplying tacks, a tack separator for separating tacks from the supplying means, means including a cam for operating the tack separator, a slide having a tack block provided with a driver passage, a tack presenter, an arm carrying the cam and tack presenter, and means for suspending the effective action of the cam and presenter when a shoe is not positioned for treatment. 115 120

30. In a machine of the class described, the combination of a raceway having two channels for supplying fastenings, a separator block, means for relatively moving the raceway and separator block to cause one or the other channel to be brought into operative relation with the separator block to 125 130

- deliver fastenings, and means for adjusting the relative position and the amplitude of relative movement of the raceway and separator block.
31. In a machine of the class described, the combination of a separator block having a passageway for fastenings, a raceway having channels for delivery of fastenings to the separator block, means for moving the raceway to present any one of the channels in operative relation with the separator block, and adjustable connections between the raceway and said moving means for changing the position of the raceway and the amplitude of its movement.
32. In a machine of the class described, a raceway for delivering two series of fastenings, means for moving the raceway to operatively position it for the delivery of either series of fastenings, adjustable connections between the raceway and moving means for changing the position of the raceway at one limit of its movement and the extent of such movement.
33. In a machine of the class described, a raceway for supplying a plurality of series of fastenings, means under control of the attendant for moving the raceway into position to effect the supply of any one of the series of fastenings, and connections between the raceway and said means including two adjustable members, one for changing the position of the raceway in its movement and the other for changing the amplitude of such movement.
34. In a machine of the class described, a raceway for supplying a plurality of series of fastenings, means under control of the attendant for moving the raceway into position to effect the supply of any one of the series of fastenings, and connections between the raceway and said means including an adjustable rod for changing the position of the raceway in its path of movement, and an adjustable arm for changing the amplitude of raceway movement.
35. In a machine of the class described, the combination of a tack-supplying means, a slide, a tack block carried by the slide and having a driver passage, a driver, means for continuously operating the slide and driver, a tack presenter, and means for moving the tack presenter to position a tack in line with the driver passage when a shoe is presented for treatment and for moving the presenter a less distance when a shoe is not presented for treatment.
36. In a machine of the character described, the combination of tack-driving mechanism, a thin edge rest, a thick edge rest arranged to swing into and out of operative position, tack-supplying mechanism arranged to deliver different kinds or sizes of tacks, an edge rest slide, a swinging block mounted on the slide, and means con-
- nected with the block for moving the slide and changing the position of the thick edge rest.
37. In a machine of the character described, the combination of tack-driving mechanism, a thin edge gage, a thick edge gage, a gage-carrying slide, a fixed plate carrying said slide, means for adjusting the fixed plate and with it the gage-carrying slide for determining the operative position of the thin edge gage, a slot and block connection between the fixed plate and slide, means for relatively adjusting the slot and block for determining the operative position of the thick edge gage, and means for relatively swinging the block and slot connection for moving the slide.
38. In a machine of the character described, the combination of tack-driving mechanism, a support having a slot, two edge gages mounted on the support constructed and arranged to be advanced and retracted, a block movable with and relative to the gages as they are advanced and retracted, and means permitting relative adjustment of the said block and slot to vary the advancing and retracting movements of the gages.
39. In a machine of the character described, the combination of tack-driving mechanism, a support having a slot, a thick edge gage and a thin edge gage constructed and arranged to be advanced and retracted relative to the support, a block engaging said slot, means for swinging the block to advance and retract the gages, and connections between the block and thick edge gage for moving the latter to and from operative position as the block is swung.
40. In a machine of the class described, the combination of tack-driving mechanism, a support, a gage-carrying slide mounted on the support, a thin gage and a thick gage carried by the slide, a swinging block mounted on the slide and having a fulcrum on the support, means for changing the fulcrum between the block and support, and means for operating the swinging block to move the slide.
41. In a machine of the class described, the combination of a tack-driving mechanism, a support, a gage-carrying slide mounted on the support, a thin gage and a thick gage carried by the slide, a swinging block mounted on the slide and having a fulcrum on the support, means for changing the fulcrum between the block and support, and means for operating the swinging block to move the slide, a toothed member movable with the block, and connections between the toothed member and thick gage for swinging the thick gage to and from operative position as the block is operated.
42. A machine of the class described, com-

- prising, in combination, tack-supplying and driving mechanism, a tack block having a driver passage, a presenter for taking tacks from the supplying mechanism and delivering them to driving position, means for shifting the tack presenter to cause it to deliver one or another kind or size of tack to driving position, and a lock for said means.
43. A machine of the class described, comprising, in combination, tack-supplying and driving mechanism, a tack block having a driver passage, a presenter for taking tacks from the supplying mechanism and delivering them to driving position, means for shifting the tack presenter to cause it to deliver one or another kind or size of tack to driving position, and a safety device to prevent shifting movement of the presenter when a shoe is in position for treatment.
44. A machine of the class described, comprising, in combination, tack-supplying and driving mechanism, a tack presenter, means for shifting the presenter to cause it to deliver one or another kind or size of tack to the inserting mechanism, and a safety device to prevent shifting movement of the presenter when a shoe is in position for treatment.
45. In a machine of the class described, the combination of fastening inserting mechanism, means for supplying fastenings of different characters, means for separating a fastening in one cycle for use in a later cycle, and means for presenting either character of fastening so separated to the inserting mechanism in the first cycle after a change in the character of fastenings to be supplied has been made.
46. In a machine of the class described, the combination of fastening inserting mechanism, mechanism for supplying fastenings of different kinds, means for separating tacks in earlier cycles to be driven in later cycles, means arranged to be changed by the operator to determine which kind of tack will be presented, and means for insuring the presentation of a fastening of the desired kind to the first action of the inserting mechanism after a change in the kind of fastenings has been made.
47. In a machine of the class described, the combination of a driver operating in each cycle, a plurality of sources of tack supply, a separator, means for causing the separator to separate a tack from either source of supply in each cycle after operation of the driver, and means for presenting a separated tack of either kind to the driver before its operation in the following cycle.
48. In a machine of the class described, the combination of a driver, means for supplying fastenings of different kinds and sizes, separating means for maintaining in separated condition a fastening of each kind supplied by the supplying means, means for selectively determining which kind of fastening shall be presented to the driver, and means for presenting a fastening of the kind selected to the first stroke of the driver after a selection is made.
49. In a machine for driving fastenings of one character in one part of a shoe and fastenings of a different character in another part of the shoe, the combination of a driver, means for supplying either of two kinds or characters of fastenings, separating mechanism acting to maintain in separated condition one fastening of each kind, means for presenting a fastening of either kind to the driver, and means arranged to be manually shifted to cause the presenting means to present selectively to the first stroke of the driver after a change is made the kind of tack for which the manual means was shifted.
50. A machine for driving fastenings of one character in one part of a shoe and fastenings of a different character in another part of the shoe, comprising, in combination, a driver, fastening supplying means for supplying fastenings of different characters appropriate for the part of the shoe being treated, a separator acting to separate fastenings from either source of supply, and means for presenting to the first stroke of the driver when a change is made from one part of the shoe to another part a previously separated fastening of the appropriate character to be driven in that part of the shoe.
51. A machine for driving fastenings of one character in one part of a shoe and fastenings of a different character in another part of the shoe, comprising, in combination, a driver, fastening supplying means for supplying fastenings of characters appropriate for the part of the shoe being treated, means for separating and holding in separated condition one fastening of each character supplied, and means arranged to be set by the operator to cause, upon operation of the machine, a fastening of either character selectively to be presented to the first stroke of the driver when a change is made from one part of the shoe to another part.
52. In a machine of the class described, the combination of tack driving means, tack separating means, a tack presenter having a plurality of tack pockets movable from position to receive a tack from the separating means to position under the driver, means operated to cause either of said pockets selectively to be presented in operative relation to the driving means, and means for causing the separating means to refill the pocket from which the tack was driven before the cycle is completed.
53. In a machine of the class described,

- the combination of tack driving means, a tack separator, means for supplying either of a plurality of kinds of tacks to the separator, a tack presenter having a plurality of tack containing recesses, means for operating the presenter to present one of the recesses in operative relation to the driver, means for causing each recess always to receive a tack of the same kind from the separator, and means which may be set prior to the tack inserting operation to determine which of the tack recesses will be moved into operative relation to the driver.
54. In a machine of the class described, the combination of a tack driver, a plurality of sources of supply for tacks of different kinds, means for receiving a tack from each source of supply, means acting to separate tacks one at a time from either source of supply and to deliver them to said receiving means, and means under control of the operator for causing any one of the separated tacks in the receiving means to be presented to the driver.
55. In a machine of the class described, the combination of a tack driver, means for supplying tacks of a plurality of kinds or sizes, means for maintaining a separated tack of each kind in readiness to be presented to the driver, and means under control of the operator for causing a change in the kind of tack to be presented to the driver and to cause a tack of the kind to which change is made to be driven by the driver on its first operation after the change.
56. In a machine of the class described, the combination of fastening inserting mechanism, means for supplying fastenings of different characters, means for separating a fastening in one cycle for use in a later cycle, means arranged to be set by the operator selectively to determine which of the separated fastenings will be presented to the inserting mechanism, and means for presenting the selected fastening to said mechanism in the first cycle after a selection has been made.
57. In a machine of the class described, the combination of fastening inserting mechanism, means for supplying fastenings of different kinds, means for separating and maintaining in separated condition fastenings of the different kinds, means arranged for selective change by the operator to determine which of the separated fastenings will be presented to the driver, and means for presenting a fastening of the selected kind to the first action of the inserting mechanism after a change in the kind of fastenings has been made.
58. In a machine of the class described, the combination of a tack driver, means for supplying either of a plurality of kinds of tacks, means for separating a tack of either kind, a member having a plurality of tack containing recesses to receive separated tacks, means for causing each recess always to receive a tack of the same kind from the separating mechanism, means for delivering the tack in any one of the recesses to the driver, and means which may be set prior to a tack inserting operation to determine which of the separated tacks in the recesses will be delivered to the driver.
59. In a machine of the class described, the combination of a tack driver, a plurality of sources of supply for tacks of different kinds, means for receiving a tack from each source of supply, means acting to separate tacks one at a time from either source of supply and to deliver them to said receiving means, and means under control of the operator for causing any one of the separated tacks in the receiving means to be presented to the driver, said separating means acting after a tack in the receiving means has been presented to the driver to deliver a tack of the same kind to the receiving means.
60. In a machine of the class described, the combination of a driver operating in each cycle, a plurality of sources of tack supply, tack separating means, means for causing the separating means to separate one tack from one source of supply or another in each cycle after operation of the driver, and means for presenting a separated tack of either kind to the driver before its operation in the following cycle.
61. A machine for driving fastenings of one character in one part of a shoe and fastenings of a different character in another part of the shoe, comprising, in combination, a driver, fastening supplying means for supplying fastenings of different characters appropriate for the part of the shoe being treated, separating means acting at the end of a cycle to separate a fastening from either one source of supply or another, and means for delivering to the first stroke of the driver when a change is made from one part of the shoe to another part a fastening separated in a previous cycle and of the appropriate character to be driven in that part of the shoe.
62. In a machine of the class described, the combination of tack driving means, tack separating means, a tack presenter having a plurality of tack pockets movable from position to receive a tack from the separating means to position under the driver, means under control of the operator to cause, upon operation of the machine, either of said pockets selectively to be presented in operative relation to the driving means, and means for causing the separating means to refill the pocket from which the tack was driven before the cycle is completed.

63. In a machine of the class described, the combination of a tack driver, a plurality of sources of tack supply, means having separate cavities each to receive and retain a tack from its appropriate source of supply, means acting to separate tacks from the sources of supply to be delivered by gravity to said cavities and acting to maintain a single tack only in each cavity, and means under control of the operator for causing any one of the separated tacks in the cavities to be delivered to the driver. 70
64. In a machine of the class described, the combination of a tack driver, means for supplying tacks of a plurality of kinds or sizes, means for maintaining a separated tack of each kind in readiness to be presented to the driver, means for presenting either of the separated tacks to the driver, and means under control of the operator for determining which kind of tack will be presented to the driver. 75
65. In a machine of the class described, the combination of a driver, a plurality of sources of supply for fastenings of different characters, means for receiving fastenings from each of said sources of supply, and means for changing the relation of said receiving means and the driver to each other to determine which character of fastenings is to be driven in a given cycle of the machine and to insure that a fastening of the desired character will be presented to the driver upon its first operation after a change in the character of fastenings has been made. 80
66. In a machine of the class described, the combination with a tack separator, a plurality of raceways shiftable to supply tacks of different kinds to the separator, and a driver for inserting tacks located at a substantial distance from the separator, said machine being organized to effect tack separation near the end of a given cycle, of means for delivering tacks from the separator to the driver, and means which may be set prior to any cycle when a change in the kind of tack used is desired to cause the delivering means automatically to present to the driver a tack of the kind desired to the first operation of the driver after the change is made. 85
67. In a machine of the class described, the combination with a tack separator, a plurality of raceways shiftable to supply tacks of different kinds to the separator, and a driver for inserting tacks located at a substantial distance from the separator, said machine being organized to effect tack separation near the end of a given cycle, of means for delivering tacks from the separator to the driver, means which may be set prior to any cycle when a change in the kind of tack used is desired to cause the delivering means automatically to present to the driver a tack of the kind desired to the first operation of the driver after the change is made. 90
68. In a machine of the class described, the combination of fastening inserting mechanism, a movable raceway having a plurality of fastening conducting channels, a separator operated to separate fastenings from the raceway, means for shifting the raceway to present either of its channels in operative relation to the separator, and means controlled by the work when presented to the fastening inserting mechanism to prevent movement of the raceway shifting means. 95
69. In a machine of the class described, the combination of a driver, means for supplying, separating and presenting either of a plurality of kinds of tacks to the driver, means arranged for manual movement to determine the kind of tack to be separated, and means operated by presentation of the shoe to the driver to lock said manual means against movement. 100
70. In a machine of the class described, the combination of a tack driver, a plurality of sources of tack supply, means for receiving a tack from each source of supply, means acting to separate tacks from the sources of supply and to deliver them to said receiving means, and means under control of the operator for causing any one of the separated tacks in the receiving means to be presented to the driver. 105
71. In a machine of the class described, the combination of a carrier plate adjustably secured to the machine frame, a slide mounted on the plate, a rock-shaft mounted on the slide, an arm connected to said shaft for lengthwise adjustment arranged to swing rearwardly and forwardly to inclined positions as the shaft is rocked and fulcrumed at its free end in a slot in the carrier plate, said slot being parallel with said arm when it is in its rearwardly inclined position, means for rocking the shaft to adjust the slide, thick and thin gages carried by the slide, and connections from the rock-shaft to one of said gages for moving it into and out of operative position. 110
72. In a machine of the class described, the combination of a member secured to the machine frame for forward and rearward adjustment and having a slot inclined to its direction of adjustment, a slide mounted on said member, thick and thin gages carried by said slide, the thick gage being arranged for movement into and out of operative position, a rock-shaft fulcrumed on the slide, an arm on the shaft arranged to turn with the shaft and for lengthwise adjustment relatively to the shaft, the free end of said arm having a fulcrum in the 115
- 120
- 125
- 130

- slot of said adjustable member, connections from said shaft to the thick gage to cause it to move into and out of operative position, the construction and arrangement being such that when the thick gage is in operative position the adjustable arm is at an inclination to the slot so that the adjustment of the arm will effect adjustment of the thick gage.
73. In a machine of the class described, the combination of fastening inserting mechanism, means for supplying selectively fastenings of different characters, fastening separating means, and means for presenting either character of separated fastening to the inserting mechanism.
74. In a machine of the class described,

a plurality of sources of tack supply for tacks of different kinds, means for inserting tacks into the work, tack separating means, means for holding a separated tack of each of the different kinds, and means for delivering either of the separated tacks to the inserting means.

75. In a machine of the class described, the combination of a plurality of sources of tack supply, tack driving means, means for separating tacks from said source of supply, and means for receiving a tack of each kind from the separating means and presenting one of said tacks to the driving means.

In testimony whereof I have signed my name to this specification.

THOMAS H. SEELY.
